US0D1029305S

(12) **United States Design Patent** (10) Patent No.: **US D1,029,305 S**
(45) Date of Patent: ** May 28, 2024

(54) **MANUFACTURED STONE SLAB**

(71) Applicant: **A&A GREEN PHOENIX GROUP JOINT STOCK COMPANY**, Hanoi (VN)

(72) Inventor: **Nang Xuan Ho**, Hanoi (VN)

(**) Term: **15 Years**

(21) Appl. No.: **29/811,288**

(22) Filed: **Oct. 13, 2021**

(51) LOC (14) Cl. **25-01**

(52) U.S. Cl.

USPC **D25/151**; D25/149

Primary Examiner — T Chase Nelson

Assistant Examiner — Sydney Margaret Parsley

(57) **CLAIM**

The ornamental design for a manufactured stone slab, as shown and described.

DESCRIPTION

The file of this patent contains one photograph executed in color. Copies of this patent with a color photograph will be provided by the Office upon request and payment of the necessary fee.

The sole FIGURE is a top plan view of a manufactured stone slab, showing our new design. The depicted surface of the manufactured stone slab is flat.
